UNITED STATES PATENT OFFICE.

SAMUEL N. McCLEAN, OF DETROIT, MICHIGAN, ASSIGNOR TO McCLEAN, SPERLIGH & UHLIG COMPANY, OF DETROIT, MICHIGAN, A PARTNERSHIP COMPOSED OF SAID McCLEAN, H. H. SPERLIGH, AND J. H. UHLIG.

SPARK-PLUG.

1,181,603.

Specification of Letters Patent.

Patented May 2, 1916.

Application filed August 5, 1912. Serial No. 713,356.

To all whom it may concern:

Be it known that I, SAMUEL N. McCLEAN, a citizen of the United States of America, residing at No. 204 Hancock avenue East, 5 in the city of Detroit and county of Wayne, State of Michigan, have invented certain new and useful Improvements in Spark-Plugs, of which the following is a specification, reference being had therein to the accompanying drawings.

The invention consists in a spark plug comprising an insulation carrying the inner electrode and a casing cast on the insulation and carrying or forming the outer electrode; 15 all as more fully hereinafter described and particularly pointed out in the claims.

In the drawings: Figure 1 is a vertical central longitudinal section through a spark plug embodying my invention, through the die in which the casing is cast and showing the plug therein; and Fig. 2 is a section on line a—a, showing the top of the plug in plan.

In the present state of the art, spark plugs 25 for gas engines are ordinarily made by forming a central porcelain insulation through which the inner electrode passes and is secured and an outer metallic casing adapted to be screwed into the cylinder-head, with a suitable wrench-hold and with various devices for securing the casing and the insulation together in such a way as to form a tight joint between the two, so as to prevent the leakage of the gases and still 30 not break the porcelain. These devices as ordinarily used embody one or more gaskets or packings, a bushing and various clamping devices, and one or more nuts and lock-nuts and lock-washers, requiring a considerable 35 expense in the manufacture of the casing and of the plug itself upon which the screw-threads are cut, both for engagement with the engine cylinder and for the clamping bushing. It has also been proposed to make 40 spark plugs by making the outer casing in the ordinary way and cast a glass insulation around the central electrode and within the casing; but in casting the glass insulation within the casing it is obvious that 45 contraction must take place in the glass, in cooling, and that such contraction will reduce the size of the insulation--and hence 50

either separate the insulation from the casing or break the latter.

My invention is intended to overcome the 55 difficulties of these prior constructions, to simplify and cheapen the cost of manufacture and to produce a more reliable and efficient spark plug than those heretofore made.

In making my spark plug I proceed as follows: A represents the insulation, which is preferably of porcelain or similar material, which may be of the ordinary construction but which I prefer to construct as 65 shown in Fig. 1 in which the outer surface of the insulation is provided with oppositely-tapering conical faces a and b, meeting at the point c, which point is preferably 70 opposite the wrench-hold d of the casing 70 B. In the insulation I place the usual electrode C, which may be secured therein in any suitable manner and is provided, as usual, at its outer end with any desired head, as D, to which the wires may be connected. This insulation is placed in suitable dies; in this case I have illustrated a metal die consisting of the two parts E and F, having the lower cavity G in which the lower portion of the porcelain will fit; and 80 I also show a sleeve H screwed into the upper end and having a bearing upon the upper tapering portion a of the porcelain, to hold the porcelain tightly in position in the mold cavity. I represents the sprue through 85 which the metal may be poured. The mold-cavity has an enlarged portion, J, preferably of hexagonal shape, or any other shape suitable to produce a wrench-hold, and the lower cylindrical portion K. has screw-threads therein, forming the nipple which 90 is to be screwed into the engine-head. It will thus be seen that there is, in this construction, a portion of the metal of the casing both above and below the shoulder C 95 and, as above described, this shoulder, or the tapering portions, are opposite the hexagonal or squared portion of the plug. The parts being thus constructed, I pour or force the metal through the sprue I into the 100 mold cavity and cast the metal upon the insulation, allowing the same to remain until it is set, so that there is formed about and upon the insulation the casing, with its

wrench-hold and screw-threads. I preferably cast the metal about the terminal of the outer electrode, as shown in Fig. 1, to do which a suitable groove is made in the 5 lower portion of the mold to hold the terminal L and the upper portion of this terminal projects into this mold-cavity, as shown at M, so that when the metal is poured therein it will flow around and support the outer 10 terminal, as clearly shown in the drawings. It is of course well-known that metal contracts in cooling, so that as the metal which is poured around the insulation cools it contracts and tightens upon the insulation. I 15 get the best results, by having the thickest metal at the wrench-hold, opposite the point where the oppositely-inclined cones meet. By casting the metal upon these oppositely-inclined surfaces I securely fasten the insulation in the casing and do away with the 20 necessity of lock-nuts, gaskets, and other devices common in the commercial spark-plug. In casting the casing I prefer to use alloys of low or medium fusing point, such as of 25 aluminum, zinc, tin and copper, as commonly used in die casting. The plug thus constructed, when removed from the die, it complete and ready for use, with screw-threads and wrench-hold, and the casing is 30 seated upon the porcelain and secured thereto not only by the casting operation but also by the shrinkage, so as to make a perfectly formed contact on the varying surfaces of 35 the porcelain, at all points; thus avoiding the use of gaskets, bushings, packings, etc., which, heretofore, it has been found neces-

sary to use in spark-plugs to prevent difficulties arising from accumulation of soot, oil, carbon, dirt, gases, and other conditions.

What I claim as my invention is:

1. A spark plug, comprising an insulator core, an inner electrode therein and an outer casing adapted for engagement with an engine cylinder and within which said core is arranged, said casing being cast upon 45 said core and shrunk thereupon to form a gas-tight joint therewith.

2. A spark-plug, comprising an insulator core having an enlarged intermediate portion and an outer casing within which said 50 core is arranged embracing said intermediate portion and in contact therewith on opposite sides of said enlargement, said casing being cast upon said insulating core and shrunk thereupon to form a gas-tight joint 55 with said enlargement upon both sides thereof.

3. A spark plug, comprising an insulator core, an inner electrode therein, an outer casing within which said core is arranged, 60 there being abutting shoulders upon said casing and core, and said casing being cast upon said core and shrunk thereupon to form a gas-tight joint between said shoulders.

In testimony whereof I affix my signature in presence of two witnesses.

SAMUEL N. McCLEAN.
